UNITED STATES PATENT OFFICE.

FRANK ROSEWATER, OF NEW YORK, N. Y.

INDICATING DEVICE.

1,075,859.

Specification of Letters Patent.

Patented Oct. 14, 1913.

Application filed April 2, 1913. Serial No. 758,403.

To all whom it may concern:

Be it known that I, FRANK ROSEWATER, a citizen of the United States, residing at New York, in the county of New York and State 5 of New York, have invented an Indicating Device, of which the following is a specification.

My invention consists in a contrivance for indicating numerals or other characters in 10 scoring games, and in spelling out words as an amusement or educational exercise also in the playing of games.

It is illustrated in the accompanying drawings, in which:

15 Figures 1 and 2 show the two opposite sides of the device when in operation. Fig. 3 shows a flat view of a containing envelop, and Figs. 4 and 5 show the opposite faces of the game disk B bearing upon either side 20 a series of characters to be indicated. Fig. 6 shows the device with the envelop A partly open and, supported by the end k, exhibiting its face bearing the score in an almost upright position as if mounted on an easel.

25 Similar letters refer to similar parts throughout the several views.

Figs. 1 and 2 show the opposite sides of the complete device with the disks B B automatically held within the adjustable envelop A, the outer edge of their peripheries, 30 projecting slightly beyond the top and bottom respectively of the casing formed by the closed envelop, passing through a series of slots located opposite each other along the 35 parallel folds. Placing the projecting ends of any disk between one's fingers it may easily be revolved and the figures or characters on its face alternately exposed through the orifice alining with it on the 40 face of the envelop A. The envelop may be kept closed through the insertion of the lip i into the incision hh, or by sealing the lid k to the lap m or it may be left partially open, as seen in Fig. 6. The device in Fig. 45 1 indicates a score of 4 games and 3 points, and in Fig. 2 the formation of the word "he."

Fig. 3 shows the envelop opened flat, exhibiting the lip i, the incision hh into which 50 the lip is to be inserted, the slots gg, gg, gg, and gg through which the edges of the disks

pass and by means of which, when the envelop is wholly or partially closed, the disks are held in place and may be revolved to suit the objects desired, and the orifices dd 55 and d'd' through which the respective figures and characters on the face of the disks B B are alternately exposed while the remaining ones remain hidden from view.

Fig. 4 shows the disk B faced with a double series of numerals, one of which has its figures each inclosed within a circle. They are alined close to the outer edge of the disk so as to alternately appear visible through the orifice d on the face of the envelop A, 60 labeled "Games", as the disk is revolved. The object of the circled series of figures is to denote that the score of points is minus or "in the hole" without impairing the service of the device in simultaneously indicating 65 the score of games and without requiring a separate disk or other device for the purpose.

Fig. 6 exhibits the device with its scoring face in a nearly upright posture, similar to 75 that of a picture mounted on an easel, and indicating a score of 4 games and 3 points, the end k acting as a support to the middle part on which the score is indicated, the disks B passing through the slotted portions 80 of the folds in the envelop, between which they are clasped and revolved.

It is obvious that if the sizes of the respective slots and disks are properly adapted to each other, the disks will be clasped 85 between the edges of the slots with sufficient firmness that while easily revolved they will remain stationary whenever stopped and will always travel in a uniform circuit, and that if the characters on the disks are 90 properly located with respect to the orifices in the envelop they will all in turn be duly exposed to view isolated from the rest and distinguished thereby for indicating. It is also obvious that the length of the envelop 95 A, the number of disks it contains and the variety of characters or series of characters on the face of the respective disks may be indefinitely extended so as to form words of varied length and a variety of numbers of 100 greatly varied numerical quantity, the individual characters of which are grouped

together through identity of size, color or some other distinguishing feature or label on the envelop. It is also obvious that the front and back could be alternately used for scoring different games, requiring different labels, such as base ball in one instance and card games in the other, by suiting the labels on the envelop and the characters on the disks accordingly and that this facility for labeling the exposed characters can be further increased by reversing the folds of the envelop and exposing the other side of the sheet it forms faced with a different series of labels or distinguishing marks. It is also obvious that when the envelop is left open, as seen in Fig. 6, not only both sides of the upper fold but both sides of the envelop also may be printed with appropriate labels suitable to the position of the respective orifices and affording four different forms of label for each orifice to suit different games to be scored or other uses; also that this duality of service is applicable to any of the uses to which the device may be put. It is also obvious that for games in which the units are not scored a cipher may be substituted on the envelop in place of an orifice and the necessity of a special disk for the units obviated, thereby reducing the relative compass and cost of the device. It is furthermore obvious that by proper alinement of the successive apertures in the face sides of the envelop the characters exposed may be formed into words on one side and numbers on the other, and that the device may thus be used as a game, the players each successively forming and naming a word on one side and requiring their respective opponents, without seeing the other side, to give the number there shown, scoring favorably if correct and unfavorably if incorrect. Based on the relation between the figures on one side and the alphabetical letters on the other, a variety of games may be devised. It is also obvious that the disks, unhampered by eyelets or other binding devices, may be made to overlap each other to an extent greatly economizing the compass of the device, and that the facility with which the disks may be taken out of the envelop readily enables their arrangement to be altered or their faces reversed; it is also obvious that the size and position of the respective orifices in the envelop A could be enlarged or altered to suit the nature of the registry to be made and the size and position of the characters on the disks. Thus by proper adaptation of the shapes and sizes of the orifices in the envelop and of the characters, abbreviations or words on the disks, the device may readily be formed into a perpetual calendar, exposing respectively the months, week days and days of the month, as needed. It is obvious that

the side *k* of the envelop could be slotted 65 vertically near its ends and the end strips fastened to the side *m* while the middle portion remained open continuing its support of the scoring side in the position shown in Fig. 6. 70

The envelop may be made of tough card board, cloth-lined card board, cambric, linen, leather or other suitable material. The disks may be made of stiff card board, celluloid or plate metal or other suitable material. 75

The advantage I claim for my device is the wide range of service it is capable of, its simplicity, its economy both in compass and cost of construction, its facility for 80 reversing faces and interchanging parts, the perfect freedom of its faces from the obtrusion of parts or marks not pertinent to its service, its facility to stand up without extraneous devices and keep the score more 85 conspicuously in view of the players, and also the facility of not only using either face of the folded envelop but also of the new faces formed by reversing the folds of the envelop and exposing the labels on its 90 other side.

I am aware that game counters have hitherto been used in which indexed rotary disks have been employed, either revolving on a pivot or spindle or else between 95 flaps formed by curved incisions or slots in a flat plate, but not revolving between the slotted parallel folds of an envelop such as herein described. I do not therefore claim the combination of an indexed rotary disk, 100 revolving either with or without a pivot, together with a slotted flat plate, but

I claim:

1. In a game counter or analogous device, the combination of the apertured envelop 105 A containing two parallel folds each provided with a series of slots arranged so that each slot shall have another slot directly opposite to it in the opposite fold, together with a series of disks of uniform diameter, 110 each placed between two opposite slots fitted so as to bear slightly against the outer edges of the disks and each also provided with a series of characters on one or both faces so located with respect to the apertures in 115 the envelop A as to be successively exposed to view through the apertures, isolated from the remaining characters, as the disks are made to revolve, all substantially as herein set forth and described. 120

2. In a game counter or analogous device, the combination of the apertured envelop A containing two parallel folds each provided with a series of slots arranged so that each slot shall have another slot directly opposite to it in the opposite fold, and with its sides *k* and *m* sealed together, together with a series of disks of uniform diameter, each

placed between two opposite slots fitted so as to bear slightly against the outer edges of the disks and each also provided with a series of characters on one or both faces so located with respect to the apertures in the envelop A as to be successively exposed to view through the apertures, isolated from the remaining characters, as the disks are made to revolve, all substantially as herein set forth and described.

FRANK ROSEWATER.
